By George C. Parker

UNITED STATES PATENT OFFICE.

HOWARD LEGGE, OF SAN FRANCISCO, CALIFORNIA.

PENCIL-BOX.

SPECIFICATION forming part of Letters Patent No. 432,831, dated July 22, 1890.

Application filed April 1, 1890. Serial No. 346,157. (No model.)

To all whom it may concern:

Be it known that I, HOWARD LEGGE, a subject of the Queen of Great Britain, residing at the city and county of San Francisco, and 5 State of California, have invented certain new and useful Improvements in Pencil-Boxes; and I do hereby declare the following to be a full, clear, and exact description of said invention, such as will enable others skilled in the 10 art to which it most nearly appertains to make, use, and practice the same.

My invention relates to certain new improvements in pencil-boxes; and it consists of the parts and details of construction as 15 hereinafter set forth and described.

My invention is especially applicable for use of school-children, and affords a convenient device for holding and carrying pencils to and from school, and at the same time provides means for the sharpening of slate or 20 lead pencils.

Referring to the drawings forming a part of this application, in which, similar letters of reference denote corresponding parts 25 throughout the entire specification and drawings, Figure 1 is a perspective view of the box opened, and Fig. 2 a view taken in cross-section.

The letter A is used to indicate the box 30 proper, which is provided with the usual lid or cover B. At one end of said box I form or provide the chamber C, within which I secure or locate the pencil-sharpener D. Insertion of pencil into the sharpener is made through 35 the opening a, made in the front thereof, as shown. The dirt or clippings from the pen-

cil fall into the chamber C, and are emptied therefrom through the escape-opening b, formed in the top b'. Upon the inner face of the cover I secure the catch c, and immediately below the same emery-block E. This is brought into use for the purpose of putting a fine point on the pencil after having been sharpened by means of the sharpener D. It will thus be seen that I form the holder and 45 sharpener in one device, thus saving the annoyance to children of carrying two or more articles for keeping their pencils in order.

Having thus described my invention, what I claim as new, and desire to secure protection in by Letters Patent of the United States, is—

1. A pencil-box having its holding-receptacle provided with an end chamber having a pencil-sharpener secured therein, substantially as and for the purpose set forth and described.

2. A pencil-box having its holding-receptacle provided with an end chamber having a pencil-sharpener secured therein, an escape- 60 opening formed in the top thereof, and a point-grinder secured to the inner face of the box-lid, substantially as and for the purpose set forth and described.

In testimony whereof I have hereunto 65 affixed my signature in the presence of two witnesses.

HOWARD LEGGE.

In presence of—

N. A. ACKER,
J. H. BLOOD.
